UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF DELAWARE.

POSITIONING DEVICE FOR CAR COUPLERS.

Application filed April 19, 1926. Serial No. 103,068.

This device relates to means for automatically positioning the coupler of a railway car by gravity.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range".

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This auto-

matic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms on couplers which members are frequently bent or broken when the couplers are not within coupling range. Such devices also reduce the number of accidents to trainmen as they are not required to go between the cars and position the coupler preparatory to coupling.

It has been found advantageous to have the coupler support cast integral with the striking casting to obtain a four sided member which reinforces the end sill, draft sill and associated parts and my device is especially adaptable to such a combined casting.

In my co-pending application I have claimed a positioning device having journaled eccentric rollers with curved surfaces engaging the associated parts but the invention claimed in this application is an improvement upon such rollers and consists in forming the member having engagement with the curved surface of the roller with means to keep the central portion of the curved surface out of contact therewith, so that the journaled roller has a rocking initial movement and a smooth rolling movement thereafter. The construction increases the efficiency of the device because it will return the coupler nearer to the longitudinal center of the car than a curved surface will do in actual service on account of commercial inequalities and, furthermore, it stabilizes the coupler in its central normal position.

In the drawings:

Fig. 1 shows a typical application of the device to a railway car.

Fig. 2 is a section on line 2—2 of Fig. 1.

Figs. 3 and 4 are diagrams showing the preferred form in normal position and extreme lateral position, respectively.

5 Figs. 5 and 6 show the rollers in Figs. 3 and 4 in detail, Fig. 6 being a section on line 6—6 of Fig. 5.

Fig. 7 shows a modified form.

Fig. 8 shows another modified form.

10 The striking casting or buffer block 2 is attached to the draft sill 3 or other part of the car body in any suitable manner and the coupler support 4 is attached thereto or preferably cast integral therewith. The coupler

15 5 rests upon the carriage 6 which engages the support in such a manner as to restrict its movement longitudinally of the car but permits its movement sidewise of the car. This is preferably accomplished by providing

20 a U-shaped support having spaced apart walls 7—8 upon which the carriage moves in one direction but is restricted in its movement longitudinally of the car.

The carriage is provided with means 10 to 25 restrict lateral movement of the coupler relative thereto. One or more rollers 12 are interposed between the support and the carriage, each of which rollers has a lower curved surface 40 having a rolling engagement with the support, the radius 41 of the curved surface being greater than half the depth of the roller so that as it rolls to one side it raises the coupler, as shown in Fig. 4. This is what is called an eccentric roller.

30 35 The support is preferably provided with an aperture 42 positioned below the center of the roller, so that the curved surface of the roller engages the opposite walls 43—44 of the aperture when the coupler is in its normal central position and stabilizes the coupler and its support. This hole also acts as a drain to prevent the accumulation of dirt, sand or other material which might clog the device and prevent its free operation.

40 45 The arrangement of the parts in normal and extreme positions is shown in Figs. 3 and 4. Figs. 5 and 6 show the roller 12 in detail.

If desired, the support may be provided 50 with oppositely disposed portions 45—46 instead of an aperture which would accomplish the same desired results. Such a construction is shown in Fig. 7.

The rollers are preferably journaled (52) 55 in the carriage and having a rolling contact with the support, as illustrated in Figs. 1—6, inclusive. However, the rollers may have rolling contact with both the support and carriage like shown in Figs. 7 and 60 8 and apertures (or their equivalents) may be used to co-operate with both rolling surfaces, as shown in Figs. 7 and 8 or with only one of them, if desired. One or a plurality of rollers may be used.

65 65 In Fig. 8 I have shown round cylindri-

cal rollers 47 which engage the opposite walls of apertures 48 in curved lower bearing surfaces or tread 49. The upper part of these rollers engage apertures 50 in the flat bearing surface or tread 51 of the carriage. 70 The various figures show numerous constructions which come within the scope of this invention.

I claim:

1. In a railway car, the combination of a 75 coupler support, a coupler carriage, one of said elements having spaced apart portions with a tread on each side thereof, and a roller supporting said carriage upon said support having a curved surface engaging the 80 spaced apart portions on said element whereby the roller is stabilized in its normal central position, the curved surface of the roller engaging one of said treads upon lateral movement of the coupler support. 85

2. In a railway car, the combination of a 90 coupler support, a coupler carriage, each of said elements having spaced apart portions with a tread on each side thereof, and a roller supporting said carriage upon said support having upper and lower curved surfaces engaging the spaced apart portions on the support and carriage, respectively, whereby the roller is stabilized in its normal 95 central position, the curved surfaces of the roller engaging some of said treads upon lateral movement of the coupler support.

3. In a railway car; the combination of a 100 coupler support, a laterally movable coupler, and a roller interposed therebetween having a curved surface engaging the support, the central part of said curved surface resting upon the opposite walls of an aperture in the support when the roller is supporting the coupler in its normal central 105 position.

4. In a railway car, the combination of a 110 coupler support, a coupler carriage, one of said elements having spaced apart portions with a curved tread on each side thereof, and a roller supporting said carriage upon said support having a curved surface engaging the spaced apart portions on said element whereby the roller is stabilized in its normal 115 central position, the curved surface of the roller engaging one of said treads upon lateral movement of the coupler support.

5. In a railway car, the combination of a 120 coupler support, a coupler carriage, one of said elements having an aperture therein forming spaced apart portions with a tread on each side thereof, and a roller supporting said carriage upon said support having a curved surface engaging the spaced apart 125 portions on said element whereby the roller is stabilized in its normal central position, the curved surface of the roller engaging one of said treads upon lateral movement of the coupler support.

6. In a railway car, the combination of 130

a coupler support, a coupler carriage, each of said elements having an aperture therein forming spaced apart portions with a tread on each side thereof, and a roller supporting said carriage upon said support having upper and lower curved surfaces engaging the spaced apart portions on the support and

carriage, respectively, whereby the roller is stabilized in its normal central position, the curved surfaces of the roller engaging some of said treads upon lateral movement of the coupler support. 10 10

ARTHUR E. SMALL.
